UNITED STATES PATENT OFFICE.

KAMEKICHI MASUDA, OF ROCK SPRINGS, WYOMING.

DESIGN FOR A BASKET.

56,825.

Specification for Design.

Patented Dec. 28, 1920.

Application filed November 3, 1919. Serial No. 335,557. Term of patent 7 years.

To all whom it may concern:

Be it known that I, KAMEKICHI MASUDA, a citizen of Japan, residing at Rock Springs, in the county of Sweetwater and State of Wyoming, have invented a new, original, and ornamental Design for Baskets, of which the following is a specification, reference being had to the accompanying drawing, forming part thereof.

The figure is a perspective view of the invention.

I claim:

The ornamental design for a basket, as shown.

KAMEKICHI MASUDA.
